UNITED STATES PATENT OFFICE.

PETER PFEIFER, OF DURHAMVILLE, NEW YORK.

CANCELING-STAMP.

SPECIFICATION forming part of Letters Patent No. 298,510, dated February 12, 1884.

Application filed September 11, 1883. (No model.)

To all whom it may concern:

Be it known that I, PETER PFEIFER, a citizen of the United States, residing at Durhamville, in the county of Oneida and State of New York, have invented certain new and useful Improvements in Canceling-Stamp, of which the following is a specification, reference being had therein to the accompanying drawings.

My invention relates to improvements in canceling and post-marking and dating devices for use upon postal and other stamps.

The object of my invention is to provide a simple, cheap, and durable device which will mutilate, permanently deface, and cancel stamps upon which it is used, the degree of mutilation being determined or regulated by a set screw which determines the depth to which the mutilating - teeth shall enter the stamp or other surface to be defaced.

Figure 1 is a side elevation of my improved canceling and post-marking device. Fig. 2 is a vertical sectional view. Fig. 3 is an edge view, and Fig. 4 is an end or bottom view.

Referring to the drawings, A is a tube, serving as the body or handle of the device, in which is secured the flexible bar B, the upper end of said bar being screw-threaded and adapted to pass through the cap C, to receive the thumb-nut D, by which the bar B is adjusted within the tube A. The bottom of the tube A is closed with a cap or sleeve, E, secured thereon by a screw, a, the face of cap E being provided with apertures b b b, which receive the serrated feet or prongs of the bar B, as will more fully appear. The filling pieces or face F of the cap E are serrated in a reverse direction from the serrations on the prongs of the bar B, and by which the paper or stamp is held while the serrations on the prongs of the bar are cutting or defacing the stamp or other surface.

G is a sleeve which encircles the tube or handle A, and is held in an elevated position by the spring H. I may, however, use a spiral spring in lieu of the spring shown. The lower end of the sleeve G is provided with a projecting flange, I, to the under side of which is secured a bar or lug, L, which projects through a slot, c, in the tube A, so as to come in contact with the bend or inclined portion d of the bar B and push the lower end of said bar forward

when the sleeve G is pushed downward on the tube A. The lower portion of the bar B is bent at right angles and divided into three or more feet or prongs, e e e, which are serrated on the lower edge, the serrations extending in a reverse direction from the serrations on the face of the cap E, and when thrust forward by the arm or lug L coming in contact with the incline d the serrations on the prongs e e e mutilate and deface the stamp. As before stated, the degree of mutilation is regulated by the thumb-nut D, the turning of which raises or lowers the bar B within the tube A and cap C, so that a thin skin of the stamp can be removed without injuring or cutting the envelope or the contents of the same. The bar B is made of steel or other suitable material which has elasticity enough to bring the feet or prongs e e into the proper working position when the lug or arm L is not in contact with the incline d. The flange I on the lower portion of the sleeve G serves as a guard to prevent the hand of the operator from slipping down.

M is a short section of tubing secured to the cap E by brazing, or in any suitable manner, in which the post-mark and date type are placed, and when the device is placed on the inking-pad the serrated prongs, as well as the type, will be inked, and in the process of mutilation the serrations on the prongs e will deposit ink on the stamp, and thus make the cancellation of the stamp more complete.

It will be noticed that the nut D extends through the cap C, and has a bushing, f, secured thereto, which prevents the bar B from being forced upward in the canceling operation.

Having thus described my invention, what I claim, and desire to secure by Letters Patent, is—

1. In a stamp-canceler, the tubular handle having apertures in its base, combined with a swinging bar suspended in said handle, and having serrated feet or prongs working in the apertures, substantially as described.

2. The tubular handle having an apertured base, combined with a swinging bar suspended from the upper part of the handle, and having serrated feet or prongs working through the apertures in the base, substantially as described.

3. The tubular handle having an apertured base, combined with a swinging bar suspended

from the upper part of the handle, and having serrated feet or prongs working through the apertures in the base, and the sliding sleeve operating to swing said bar, substantially as 5 described.

4. The swinging bar suspended from the upper end of the tubular handle, having serrated feet or prongs at its lower end, and an intermediate bend or incline, in combination with 10 said handle, and its sliding sleeve having a lug operating on said incline, substantially as described.

5. The swinging bar adjustable at the upper end of the tubular handle, and having serrated 15 feet or prongs at its lower end, in combination with said handle having apertures in its base

through which said prongs work, substantially as described.

6. In a device for canceling stamps, an apertured base having on its face serrations inclined in one direction, combined with movable feet or prongs serrated on their lower faces in an opposite direction, whereby the article is held in position while the movable feet or prongs cancel or deface the same, as set 20 25 forth.

In testimony whereof I affix my signature in presence of two witnesses.

PETER PFEIFER.
